UNITED STATES PATENT OFFICE.

ALBERT N. WOODRUFF, OF NEW YORK, N. Y.

COPY-HOLDER.

1,389,411.

Specification of Letters Patent. Patented Aug. 30, 1921.

Application filed July 29, 1920. Serial No. 399,672.

To all whom it may concern:

Be it known that I, ALBERT N. WOODRUFF, a citizen of the United States, and a resident of the city of New York, borough of Manhattan, in the county and State of New York, have invented a new and Improved Copy-Holder, of which the following is a full, clear, and exact description.

The present invention relates to new and useful improvements in copy-holders, and it pertains more particularly to a device for supporting in a visual position, stenographers' note-books, and other copies.

It is the primary object of the present invention to provide a copy-holder with a marker, which marker is movable with respect to the copy carried by the holder.

It is a still further object of the invention to provide new and novel means by which the movement of the marker may be adjusted to steps of various lengths.

With the above and other objects in view, reference is had to the accompanying drawings, in which—

25 Fig. 1 is a front elevation of a copy-holder constructed in accordance with the present invention;

Fig. 2 is a rear view with a portion of the mechanism broken away;

30 Fig. 3 is a side elevation of the copy-holder constructed in accordance with the present invention;

Fig. 4 is a detail sectional view taken on the line 4—4 of Fig. 2, and

35 Fig. 5 is a detail sectional view taken on the line 5—5 of Fig. 1.

Referring more particularly to the drawings, the device comprises a writing bed 10, carried by a support which consists of a pair 40 of base members 11 having angularly disposed rear legs 12, and pivotally secured to the writing bed 10, as at 13. The forward ends of the base members 11 are looped and bent upwardly to provide legs 14.

45 Pivots carried by the looped portions of the base members 11, is a supporting bracket 15, substantially U-shaped, and the looped portion of said U-shaped bracket 15 is adapted to engage beneath the forward

50 end of the writing bed 10 to support the latter in inclined position. Each of the legs of the U-shaped member 15 is coiled about the looped portion of the base 11 as indicated by the reference character 16, and said legs

55 are further provided with hooks 17 adapted

to engage the legs 14 of the looped portions of the base members 11 to limit the movement of the U-shaped member in one direction.

To provide for securing a copy-book 18 in place on the writing bed 10, a clamping member 19 is employed, and said clamping member comprises a substantially L-shaped member, the legs of which are slidable in guides 20 carried by the writing bed, as more clearly shown in Figs. 1 and 2. The long leg 21 of the L-shaped clamping member projects parallel with one of the side edges of the writing bed 10 and is provided on its rear end with an operating button 22, and secured to this operating button 22 and projecting inwardly of the writing bed 10, is a guide member 23.

Secured to the rear end of the writing bed 10, as by means of a clip 25 and a bolt or screw 26, is a spring member 27, and said spring member 27 has two legs 28 and 29. The leg 28 of this spring member 27 engages the operating button 22 of the L-shaped member 19 to maintain the same extended in order that clamping action may be had on the copy-book 18. By this construction, it will be apparent that as the operating button 22 is forced against the action of the spring 27, the L-shaped clamping member 19 will be released from the copy-book and the same will be free to be removed.

Rigidly secured to the rear of the writing bed 10, is a screw-threaded rod 30, and said screw-threaded rod 30 extends throughout the length of the bed and is rigidly secured to the ends thereof as by means of collars or nuts 31. To fill the space between the screw-threaded rod 30 and the writing bed 10, a plate 31' is interposed, as more clearly shown in Fig. 4. Extending longitudinally of the bed 10 on its rear face in parallelism to the screw-threaded member 30, is a screw-threaded member 32, said member being reciprocatively mounted with respect to the writing bed 10. This member 32 has one of its ends projecting beyond the end of the writing bed 10, as indicated by the reference character 33, and said projecting end is provided on its extremity with an operating button 34. This screw-threaded member 32 is rigidly carried by means of a flat plate 35, and said flat plate 35 is slidably mounted between guides 36 and 37 carried on the rear face of the writing bed 10. To main-

tain the reciprocating threaded member 32 in extended position, the leg 29 of the spring member 27 is bent thereabout as indicated by the reference character 38, and interposed 5 between the operating button 34 of the screw-threaded member 32 and the end of the writing bed 10, is an adjustable nut 40, by means of which the stroke of said reciprocating member may be limited or regulated.

The reference character 45 designates the marker, which comprises a piece of wire looped as indicated by 46, in order that it may pass around behind the writing bed 10. 15 As shown on Fig. 2, this looped portion 46 of the marker 45 is mounted in clips or bearings 47, and said portion is again looped as indicated by the reference character 48 to provide an arm 49, which overlies the two 20 screw-threaded members 30 and 32. The clips 47 in which the marker is journaled are mounted on a carriage 50. One end of the carriage 50 is projected beneath a flange 51 formed on one side edge of the writing bed, 25 as indicated at 52. The opposite end of the carriage 50 is provided with a guide 24, said guide comprising two plates arranged in right-angular relation to each other in such a manner as to provide a member cross- 30 shaped in cross-sectional form. One of the arms of the cross projects between the long leg 21 of the L-shaped member, and the other member having two spaced arms 53 which overlie the long leg 21 of the L-shaped member as shown in Fig. 1.

To maintain the marker 45 at all times in contact with the copy, a coil spring 54 is provided, said coil spring having one of its arms 55 exerting a pressure against the leg 49 of 40 said marker.

Mounted on the carriage 50 are two pivoted dogs 56 and 57. These dogs 56 and 57 are adapted to engage the screw-threaded members 32 and 30, respectively, and to 45 maintain them in engagement with their screw-threaded members, a coil spring 58 is employed.

The device operates in the following manner:

50 With the parts in the position shown in Figs. 1 and 2, when it is desired to move the marker, the operating button 34 of the screw-threaded member 32 is depressed against the action of the spring 29. This moves the 55 screw-threaded member 32 relatively to the carriage 50, the dog 56 lifting to permit of the movement of the screw-threaded member 32 in this direction. Upon releasing the screw-threaded member 32, the pivoted dog 60 56 engages the flanges of said screw-threaded member and upon said screw-threaded member 32 returning to normal position, under the influence of the spring 29, the carriage will be moved with it. The dog 57 prevents the movement of the carriage when the

screw-threaded member 32 is depressed but permits of a free movement of the carriage when the same is moved by a reciprocation of the screw-threaded member 32, since when moving in this direction the dog 57 slides 70 freely over the screw-threaded member 50.

When it is desired to position the marker at the top of the writing bed 10 in order to start a new sheet on the copy, it is only necessary to grasp the looped portion 46 thereof, 75 and rock it in its bearing clips 47. This action causes the looped end 49 of the marker to engage the pivoted dogs 56 and 57 and rock them about their pivotal point to a position where they disengage their respective 80 screw-threaded members, and permit of a movement of the carriage from the bottom to the top of the writing bed 10.

By adjustment of the nut 40, it will be apparent that the stroke of the screw-threaded 85 member 32 may be varied and that as the stroke is varied, the distance of movement of the marker 45 will likewise be varied, thus adapting the device for use in connection with copies having varying spaces between the lines of writing thereon.

From the foregoing it will be apparent that the present invention provides a new and improved copy-holder by means of which the operation of copying is greatly facilitated, and, at the same time, a device is provided which is simple in both construction and operation.

Claims:

1. In a copy holder, a writing bed, guides 100 formed on the writing bed, a carriage slidably mounted in said guides, a stationary screw-threaded rod carried by the writing bed, a second screw-threaded rod carried by the writing bed and reciprocatively 105 mounted with respect thereto, a plurality of pawls mounted on the carriage, resilient means for normally maintaining one of said pawls in engagement with the stationary screw-threaded rod and the other 110 with the reciprocating screw-threaded rod, and means mounted on the carriage and adapted for engagement with said pawls for moving one end thereof out of engagement with their respective screw-threaded rods 115 for permitting movement of the carriage longitudinally of the writing bed.

2. A copy holder comprising a writing bed, a carriage mounted for reciprocating movement longitudinally of the writing bed, 120 a screw-threaded rod rigidly carried by the writing bed, a reciprocating screw-threaded rod carried by the writing bed, a line indicator carried by the carriage and adapted to be moved longitudinally of the writing bed upon movement of the carriage, a plurality of pawls mounted on the carriage and adapted to engage said screw-threaded rods whereby 125 movement of the carriage in one direction 130

- is provided, and an extension formed upon one end of the line indicator and adapted to occupy a position adjacent said pawls whereby said extension may be moved into engagement with the pawls to disengage them from their respective screw-threaded rods to permit movement of the carriage in either direction longitudinally of the writing bed.
- 10 3. A device of the character described comprising a writing bed, a carriage reciprocatingly mounted thereon, a rod rigidly carried by said bed, a second rod reciprocatively mounted on the bed, a plurality of 15 pawls mounted on the carriage, and adapted to engage said rods to prevent movement of the carriage longitudinally of the bed, a line indicator pivotally mounted on the carriage and projecting to the front of the writing bed, and means comprising an extension of the line indicator said extension lying adjacent the pawls in such a manner that as the line indicator is rocked about its pivotal points, said extension will engage 20 the pawls and cause their disengagement from their respective rods to permit of free movement of the carriage longitudinally of the writing bed in either direction.

ment from their respective rods to permit of free movement of the carriage longitudinally of the bed in either direction. 25

4. A device of the character described comprising a writing bed, a rod rigidly carried by said bed, a second rod reciprocatively mounted on the bed, a plurality of 30 pawls mounted on the carriage and adapted to engage said rods to prevent movement of the carriage longitudinally of the bed, a line indicator pivotally mounted on the carriage and projecting to the front of the writing bed, and means comprising an extension of the line indicator said extension lying 35 adjacent the pawls in such a manner that as the line indicator is rocked about its pivotal points, said extension will engage 40 the pawls and cause their disengagement from their respective rods to permit of free movement of the carriage longitudinally of the writing bed in either direction.

ALBERT N. WOODRUFF.
